The design is characterized by the specifically shaped back rest in combination with the curved rear leg brace and the double curvature of the seat cushion, all as shown.

We claim:

The ornamental design for an easy chair, as shown and described.
